UNITED STATES PATENT OFFICE

97,441

DESIGN FOR A COMPOSITE CONTAINER

James W. Scully, Seattle, Wash.

Application April 17, 1935, Serial No. 56,431

Term of patent 7 years

To all whom it may concern:

Be it known that I, James W. Scully, a citizen of the United States of America, residing at Seattle, in the county of King and State of Washington, have invented a new, original and ornamental Design for a Composite Container, of which the following is a specification, reference being had to the accompanying drawing and description, forming part hereof.

Figure 1 is a top perspective view, and Figure 2 is a side elevational view of a composite container showing my new design.

The characteristic feature of my design resides in the arrangement of a plurality of individual relatively shallow boxes, each box complete with its own individual telescoping cover; the plurality

of boxes being superimposed and held in fixed group relation by telescoping end cover members disposed one at each end of the superimposed group; these end cover members being of a color contrasting with that of the superimposed boxes and extending over only relatively small areas of the end portions of said superimposed group of boxes, leaving the intermediate side portions of the boxes exposed to view.

I claim:

The ornamental design for a composite container, as shown and described.

Signed at Seattle, King County, Washington, this 12th day of April, 1935.

JAMES W. SCULLY.
